CLAIM

The ornamental design for a treatment tip of a cooling treatment system as shown and described.

DESCRIPTION

FIG. 1 is an isometric view of a treatment tip of a cooling treatment system.

FIG. 2 is another isometric view of the treatment tip of FIG. 1.

FIG. 3 is a side view of the treatment tip of FIG. 1.

FIG. 4 is another side view of the treatment tip of FIG. 1.

FIG. 5 is another side view of the treatment tip of FIG. 1.

FIG. 6 is another side view of the treatment tip of FIG. 1.

FIG. 7 is a top view of the treatment tip of FIG. 1.

FIG. 8 is a bottom view of the treatment tip of FIG. 1; and,

FIG. 9 is a cross-sectional view of the treatment tip of FIG. 1, the treatment tip being rotationally symmetric about its central vertical axis.

The broken lines indicate unclaimed portions of the treatment tip that form no part of the claimed design.
